UNITED STATES PATENT OFFICE.

EDWARD MELTZER, OF NEW YORK, N. Y., ASSIGNOR, BY MESNE ASSIGNMENTS, TO
HYDROCARBON BURNER & MANUFACTURING COMPANY, A CORPORATION OF
NEW JERSEY.

HYDROCARBON-BURNER.

1,152,746.

Specification of Letters Patent.

Patented Sept. 7, 1915.

Application filed November 19, 1908. Serial No. 463,814.

To all whom it may concern:

Be it known that I, EDWARD MELTZER, a citizen of the United States, residing in the city of New York, borough of Manhattan, county and State of New York, have invented a certain new and useful Hydrocarbon-Burner, of which the following is a specification.

This invention is a hydrocarbon vaporizer and burner, and, more particularly, it is designed as an improvement, in a certain particular, upon the apparatus disclosed in a prior application filed by me on July 3, 1908, Serial No. 441,818. In the apparatus described in the aforesaid application, steam or air is supplied under pressure to a series of jet nozzles from a chamber in communication with said nozzles, and jets are projected by these nozzles into a mixing chamber so that said jets operate to entrain and carry a combustible vapor, preferably resulting from the vaporization of oil brought into contact with a heated surface, such as a vaporizing plate.

Practical experience with a vaporizer and burner of the type described shows that the jet nozzles, or the orifices through which the jets are projected, are liable to become clogged or obstructed by the deposit of sediment therein or by the formation of scale in the orifices or on the surfaces adjacent thereto, whereby certain or all of the nozzles are rendered inoperative and it becomes necessary to stop the apparatus temporarily for the purpose of cleaning the parts or of repairing them.

The object of the present invention is to overcome the foregoing objections, and to this end it consists in the employment of means whereby the deposits of sediment in the nozzles or orifices may be removed quickly and without arresting the operation of the vaporizer and burner.

In the accompanying drawings I have illustrated one practical embodiment of the invention, but the construction shown therein is to be understood as illustrative, only, and not as defining the limits of the invention.

Figure 1 is a plan view of a vaporizing burner embodying this invention. Fig. 2 is a vertical section through a part of the burner shown in Fig. 1. Fig. 3 is a vertical cross section on the line 3—3 of Fig. 2, and

Fig. 4 is an enlarged detailed sectional view, partly in elevation, showing one of the cleaning stems adapted for operation in one of the injecting nozzles.

The burner, or as it may be designated, a combined vaporizer and burner, of the class described in the aforesaid application is shown in Figs. 1 and 2, by reference to which it will be seen that said burner consists of a cylinder, A, provided at one end with a substantially frusto conical head, a, and a vaporizing plate, B. Said vaporizing plate is provided with a plurality of openings, b, and with a depression or cavity, b', (see Fig. 2). The head, a, of chamber, A, is provided with a number of openings, a', for the ingress of air into chamber, A, and as disclosed in the aforesaid application, said head, a, is provided with other openings, c, which are adapted to be partly or wholly closed by suitable shutters, C. Chamber, A, is provided, also, with a lining composed of heat resisting material, d, and furthermore, said chamber is furnished at its lower rear part with a shelf or table, d'.

D designates a casting which is supported on the shelf, d', and is positioned in co-operative relation to vaporizing plate, B, (see Fig. 2). This casting is provided with an interior chamber, e, preferably annular in shape, and with this chamber, e, communicates means for supplying steam or air to said chamber for the purpose of maintaining steam or air under pressure therein. As shown a steam pipe, E, is attached to casting, D, so as to communicate with pressure chamber, e, whereby steam may be supplied to said chamber, e. If desired, the pipe, E, may be associated with a super-heating coil as disclosed in the aforesaid application, but for some purposes, the super-heating coil is dispensed with, and live steam is supplied under boiler pressure by pipe, E, to pressure chamber, e.

Casting, D, is provided with a front plate, e', and a rear plate, e'', said front and rear plates being preferably integral with casting, D, and forming the walls of pressure chamber, e. Front plate or head, e', is provided with a series of openings, f, corresponding in number and position to openings, b, of vaporizing plate, B, and in these openings, f, are screwed jet nozzles, F. Said nozzles are tapered and they extend for-

wardly from plate or head, e' , into the openings, b , but said nozzles do not fill said openings, thus leaving free spaces between the walls of openings, b , and outer surfaces 5 of nozzles, F .

The salient feature of the present invention consists in the employment of means for removing any sediment which may lodge or accumulate in openings, b , of the vaporizing plate, B , or in the passages of nozzles, F , whereby the steam passage or passages are kept in an open, free and unobstructed condition so that steam will pass into the chamber of cylinder, A , and the combustible vapor will be entrained by the steam jets, as will presently appear.

As shown, the sediment removing means consists of stems or spindles, G . Each spindle operates in an opening, g , which is 20 provided in the outer end plate or head, e^2 , said opening, g , of plate, e^2 , being in register with opening f , of plate, e' , so that a group of openings, b , f , g , are in alinement lengthwise of the burner. The opening, g , receives 25 the gland, g' , of a stuffing box, the latter having a packing, g^2 , as shown in Fig. 4. Stem, G , passes through the stuffing box so that it may be reciprocated or moved lengthwise in the stuffing box and across pressure 30 chamber, e . Said stem is provided at its outer exposed end with a knob or head, h , and this knob is adapted to be grasped by hand when it becomes necessary to reciprocate the stem or spindle. As shown in Figs. 35 2 and 4 a series of stems, G , are employed, one for each nozzle, F , and each stem is supported by the stuffing box in alinement with its nozzle, F . Normally, stems, G , are drawn away from nozzles, F , so that steam will 40 pass freely from pressure chamber, e , into nozzles, F , but should it become necessary to remove a deposit of sediment from nozzle, F , the attendant presses stem, G , inwardly. This operation causes the forward end of 45 stem, G , to pass through nozzle, F , and to eject therefrom any matter or sediment which obstructs the steam passage in said nozzle. Obviously, the openings, b , in vaporizing plate, B , may also become obstructed by the deposit of sediment, and it is necessary, therefore, to remove sediment from 50 said jet openings, b . The stems employed according to this invention may be forced entirely through jet nozzles, F , and also through jet openings, b , thus simultaneously 55 cleaning out the passages of the jet nozzles and the openings, b , in vaporizing plate, B .

It is to be observed that stems, G , operate across pressure chamber, e , and that each 60 stem is exposed at one end outside of the burner. The stuffing boxes preclude leakage of steam from pressure chamber, e , around stems, G .

As shown more clearly in Fig. 2 casting, 65 D , is provided with a hub or sleeve, i , and

into this sleeve is fitted and secured a short tube, I , the inner end of which is positioned opposite to depression, b' , of vaporizing plate, B . The outer end of tube, I , is closed by a head, i' , and to this head is attached one 70 end of the feed pipe, J , the latter being adapted to supply fuel, preferably, oil, into tube, I . Oil is supplied under pressure by pipe, J , and it impinges on the vaporizing plate, B , whereby liquid is vaporized by contact with said plate, B . 75

K designates a pipe attached to casting, D , and communicating with chamber, e , so as to carry off water of condensation which may accumulate in chamber, e . Pipes J , K , 80 are provided with cocks, j , k , respectively.

The operation of the apparatus will be apparent from the foregoing description taken in connection with the drawings, but it may be described as follows:—Steam 85 from any suitable source is supplied to pipe, E , and conveyed thereby to chamber, e , whereas oil is fed by pipe, J , and projected through tube, I , in the form of a spray or jet against plate, B . The steam issues from 90 nozzles, F , in the form of jets which are projected through openings, b , into the mixing chamber of cylinder, A , and the steam jets entrain the vaporized fuel into said mixing chamber. Simultaneously with 95 these operations, air is drawn into the chamber of cylinder, A , and the steam, fuel and air are commingled in said chamber and burned therein. The combustion thus set up heats the apparatus, and plate, B , thereof, 100 and in the operation of said apparatus, plate, B , vaporizes the oil thrown against it, the vaporized oil being entrained by the jets from nozzles, F , through openings, b , into the chamber of cylinder, A . 105

As previously stated, one or more of the openings, b , and nozzles, F , either separately or conjointly, may become clogged by the deposit of sediment, and this ordinarily throws out of operation one or more of the 110 jets. My improvement overcomes this defect for the reason that stems, G , may be operated easily and quickly to clean out nozzles, F , and openings, b , thus removing the sediment therefrom. Furthermore, these 115 operations of cleaning the parts from sediment do not require the operation of the burner to be stopped, for the reason that the stems, G , may be operated at will and while the burner is in operation. 120

Having thus fully described the invention, what I claim as new, and desire to secure by Letters Patent is:

1. In a hydrocarbon burner, the combination of means for supplying air thereto and 125 for regulating the quantity of air, an oil chamber, means for supplying oil to the oil chamber, the forward wall of said oil chamber forming a vaporizing plate, said vaporizing plate having a solid central por- 130

- tion and an exterior perforated portion, a steam chamber concentric with and surrounding said oil chamber whereby the oil in the oil chamber may be heated prior to vaporizing it, nozzles leading from said steam chamber and alining with the perforations in the vaporizing chamber, and manually operated means for removing obstructions from said nozzles.
- 10 2. In a hydrocarbon burner, the combination of an oil chamber, means for supplying oil to the oil chamber, the forward wall of said oil chamber forming a vaporizing plate, said plate being provided with a plurality of perforations, a steam chamber substantially concentric with and exterior of said oil chamber whereby the oil in the oil chamber may be heated, nozzles leading from the steam chamber and in alinement with the perforations in the vaporizing plate, manually operated means for removing obstructions from said nozzles and perforations, air supply means for the burner,

and valve mechanism for regulating said air supply.

3. In a hydrocarbon burner, the combination of concentric oil and steam chambers, the forward wall of said oil chamber forming a vaporizing plate and extending in front of the steam chamber, a mixing chamber forwardly of said vaporizing plate, an air inlet to said mixing chamber positioned forwardly of said vaporizing plate, apertures in said vaporizing plate and leading into said mixing chamber, steam nozzles leading from the steam chamber and in alinement with the apertures in the vaporizing plate, and reciprocating members for cleaning said nozzles and apertures.

In testimony whereof I have signed my name to this specification in the presence of two subscribing witnesses.

EDWARD MELTZER.
